UNITED STATES PATENT OFFICE.

ALFRED MAGUIN, OF CHARMES, NEAR LA FÈRE, FRANCE.

FEED DEVICE FOR ROOT-CUTTERS PROVIDED WITH DRUMS.

1,169,981.

Specification of Letters Patent.

Patented Feb. 1, 1916.

Application filed April 24, 1913. Serial No. 763,421.

To all whom it may concern:

Be it known that I, ALFRED MAGUIN, a citizen of the French Republic, residing at Charmes, near La Fère, Aisne, France, have 5 invented a certain new and useful Feed Device for Root-Cutters Provided with Drums, of which the following is a specification.

In machines for slicing beetroots or other 10 roots for the purpose of the extraction of sugar by the diffusion process the chief care is to obtain regularity of formation of the slices cut by the member carrying the cutting blades: now, the principal cause of the 15 poor quality of the slices cut is lack of regularity in feeding the roots into contact with the member which carries the cutting blades.

In the so-called drum root-cutters different 20 devices have successively been employed for securing this regularity of contact of the beet-roots with the cutting surface; these devices have given good results, but they do not secure absolutely perfect progress 25 of the operation.

The device, however, which is the object 30 of the present invention allows of obtaining the maximum of efficiency; it is characterized by the combination with a special 35 form of the hopper into which the beetroots pass for delivery to the root-cutters, of a screw which exerts a pushing effect and which is provided at the bottom of this hopper and is set in motion by the shaft of the root-cutters themselves by means of a gear 40 wheel and pinion. In order not to set up an abnormal strain when changing the knife-carriers and when the cutting portion of the root-cutters is rotated in the opposite 45 direction, the screw is connected to the shaft which supports it by means of a ratchet device which only acts in the direction of rotation for operation of the machine.

50 In the accompanying drawings is shown a constructional form of the present invention.

Figure 1 is a horizontal section through A—B of Fig. 2; Fig. 2 is a vertical section through C—D—E—F in Fig. 1; Fig. 3 is an elevation showing the root-cutters from the side of the hopper; Fig. 4 is a plan view

of the exterior charging hopper; finally Fig. 5 is a detail showing the method of mounting the feeding screw on its axis, with 55 the ratchet device.

As shown on these figures, the hopper 1 is provided with a substantially cylindrical part 2 into which the beetroots fall before entering the root-cutters; in the center of 60 this part 2 is provided a screw formed by a portion of a worm 3; this screw is mounted on a shaft 4 on which is keyed a gear wheel 5 receiving motion from the shaft 7 of the root-cutters through a pinion 6. 65

During the period of operation, the screw thus driven by the rotation of the shaft of the root-cutters, forces the beetroots regularly and irresistibly forward laterally through the casing 12 into the interior hopper and moves them regularly against the cutting surface. When the drum stops, the screw also stops, thus ending the period of feeding. In order to avoid the abnormal strain which it would be necessary to exercise when the root cutters are rotated in the 70 opposite direction from the direction for operation for the purpose of changing the knife carriers, the screw has been mounted on a sleeve 8 surrounding the shaft 4; a 75 spring 9 confined between a projection of the sleeve 8 and a stop 10 which can be regulated and which is provided on the shaft 4, tends constantly to press the sleeve 8 against the inclined portion of a shoulder 80 85 11 of the shaft 4. This inclined portion is so provided that the shaft 4 drives the endless screw 3 when the shaft rotates in the direction of operation and does not drive in the opposite direction, its projection acting 90 on the sleeve 8 against the action of the spring 9. This ratchet device thus insures the stopping of the screw when the root-cutters are rotated in the opposite direction to the direction for operation. 95

What I claim as my invention and desire to secure by Letters Patent is:—

A machine for slicing beetroots and the like consisting of a worm horizontally disposed, a shaft upon which said worm is 100 mounted, a ratchet device by means of which the said worm is connected to the shaft so that the said worm may rotate in one direction only, a cylindrically shaped

channel within which the said shaft and worm are mounted, a shaft upon which the cutters are mounted, said shaft being disposed eccentric with but parallel to the worm shaft and gear by which the movement of one shaft is transmitted to the other.

In testimony whereof I have hereunto signed my name to this specification in the presence of two subscribing witnesses.

ALFRED MAGUIN.
